to Allied Plastics Company, Los Angeles, Calif.,
a copartnership

Application May 28, 1945, Serial No. 119,767

Term of patent 3½ years

(Cl. D86—10)

To all whom it may concern:

Be it known that I, Walton B. Crane, a citizen of the United States of America, residing at Beverly Hills, in the county of Los Angeles, State of California, have invented a new, original, and ornamental Design for a Compact, of which the following is a specification, reference being had to the accompanying drawing, forming a part thereof.

Figure 1 is a top perspective view of a compact in closed position, showing my new design;

Figure 2 is a top plan view thereof in closed position;

Figure 3 is a top perspective view thereof in open position;

Figure 4 is a side elevational view thereof in open position, and

Figure 5 is a side elevational view thereof in closed position.

I claim:

The ornamental design for a compact, substantially as shown.

WALTON B. CRANE.
